UNITED STATES PATENT OFFICE.

ADOLF E. AESCHLIMANN, OF TAYLOR, TEXAS.

GATE.

No. 874,376.

Specification of Letters Patent.

Patented Dec. 24, 1907.

Application filed August 27, 1907 Serial No. 390,288.

To all whom it may concern:

Be it known that I, ADOLF E. AESCHLIMANN, residing at Taylor, in the county of Williamson and State of Texas, have invented certain new and useful Improvements in Gates, of which the following is a specification.

My invention relates to certain new and useful improvements in gates of the vertically opening balanced type and it primarily has for its object to provide a gate of this character of a very simple and effective construction, which can be easily and cheaply manufactured and which will readily and effectively serve its intended purposes.

In its generic nature, my invention comprises a gate consisting of two sections mounted in posts at the sides of the road and adapted to open and close from and toward one another, the sections being adapted to be folded when in their open position, and means are also provided for locking the sections both in their open and closed positions, and means for first releasing the locking device and then tilting the gates on their fulcrums to open or close the same, as the case may be.

My invention also includes a positive connection between the tilting lever and the gates whereby the motion of the tilting lever will be simultaneously imparted to each of the gate sections.

In its more specific nature, the invention embodies certain novel constructions, combinations and arrangement of parts all of which will be first described in detail and then be specifically pointed out in the appended claims, reference being had to the accompanying drawings, in which:-

Figure 1, is a perspective view showing my invention with the gate closed. Fig. 2, is a side elevation of a modified form of my invention, the gate being in its closed position. Fig. 3, is a detail perspective view showing the locking mechanism. Fig. 4, is a similar view showing the means for securing the two gates at their points of juncture. Fig. 5, is a detail perspective view of a modified form of my invention. Fig. 6, is a perspective view of the form of my invention shown in Fig. 1, the gate being open. Fig. 7, is a side elevation of the form of my invention shown in Fig. 2, the gate being open.

Referring now to the accompanying drawings, in which like letters and numerals of

reference indicate like parts in all of the figures, 1 designates the main supporting posts which are adapted to be sunk into the ground to a satisfactory depth at each side of the road, and to which the gate posts 2 are bolted, or otherwise secured, as at 1^a, the posts 2 being formed of parallel bars 2^a between which the gate sections 3 and 4 are fulcrumed. One of the gate posts 2 is extended upwardly to a greater height than the other and is connected at the top by a spacing block 2^b having a bearing portion 2^c to which the gate operating lever 5 is fulcrumed, as at 5^a in a manner which will be clearly understood by referring to the drawings.

Each gate section comprises parallel horizontal bars 3^a and 4^a, connected at their adjacent ends by the central abutting bars 3^b and 4^b respectively which posts are formed of a pair of parallel bars pivotally secured to the horizontal bars 3^a and 4^a by bolts 3^c and 4^c respectively, as shown. The bar 4^b is provided with a spring metal locking member 4^d which is adapted to have its end 4^e projected over the top 3^d of the bar 3^b to lock the bars 3^b and 4^b together, guard members 4^f being provided on the bar 4^b and embracing the post 3^b to prevent the locking member 4^d becoming jammed and inoperative. On long gates intermediate vertical supporting bars 3^g and 4^g respectively may be provided, as shown in modification, Fig. 2, and these bars are pivoted to the horizontal bars 3^a and 4^a respectively, in a manner similar to that of the posts 3^b and 4^b.

3^m and 4^m respectively designate metallic bearing clips which are secured to the horizontal bars 3^a and 4^a respectively of the gate sections 3 and 4, and through which the pivot bolts 2^m which project through the posts 2, pass and thus pivotally connect the gate sections 3 and 4 with the posts 2, it being understood that all the bars 3^a and 4^a of the respective gate sections 3 and 4 are parallel as are also the posts 2, bars 3^b—4^b and the bars 3^g and 4^g, when such are used.

6 designates foot members which may be the lower ends of the bars 3^b and 4^b or they may be in the nature of metallic members secured to the lower ends of said bars, and having their lower portions diverging to rest upon the V-shaped or beveled upper surfaces 7^a of a center block 7 which is adapted to be sunk into the ground midway between the 110

posts 2 and only have its upper surface 7^a exposed.

8—8 designate bearing clips secured to the respective bars 2^a of the posts 2 in which the 5 upper bars 3^a and 4^a of the gate sections 3 and 4 respectively are fulcrumed instead of being fulcrumed directly to the posts 2. The bars 3^a and 4^a have projecting members 9 which diverge at their outer ends carrying 10 counterweights 10 to counterbalance the gate sections 3 and 4.

11 designates a latch member fulcrumed at 11^a to the upper gate bar 4^a of the gate section 4, and provided with notches 11^b and 15 11^c respectively which are adapted at times, to engage with the locking bar 12^a of a U-shaped locking member 12 that is secured to the post 2 and which locks the gate section 4 so as to hold the gate section 4 either in its 20 open or closed position, as the case may be.

13 designates a latch releasing member which is endwise slidable in bearings 14, carried by the post 2 and is normally spring 25 pressed out of engagement with the latch 11 by a spring 13^a which is mounted on the member 13, as clearly indicated in Fig. 3, of the drawings, the member 13 having a passage 13^b for the end of the latch 11. The latch release member 13 has a projection 13^a 30 that passes through a slot 12^m in the member 12 and is furthermore provided with a finger 13^m which engages the underside of the latch 11. These parts are shown particularly in 35 Fig. 3 of the drawings, parts thereof being broken away to more clearly show the engagement between the latch 11 and the member 12.

The operating lever 5 which is pivotally mounted at 5^a at the top of the post 2, as before stated, carries a double bell crank lever 15 which has its horizontal portions 15^a connected with the member 13 by wires or ropes 16, or in any other manner desired. Each 40 end of the lever 5 is slotted as at 5^x, to receive the bell crank levers 16^b, which are pivotally mounted at 16^a therein and are connected with the centrally mounted double bell crank lever 15 by ropes or cables 17, as shown. Pull ropes or cables 18 are connected to the other ends of the bell crank levers 16^b and are adapted to be engaged by the operator when it is desired to manipulate the gate.

19 designates a tubular casing which is 55 mounted in apertures in the posts 1 and the center block 7 and projects from one post 1 to the other through the center block 7 and this casing 19 may be, in practice a two inch pipe in which the gate operating shaft 28 is 60 mounted. The shaft 20 may be also constructed of pipe material of lesser diameter than that of the casing 19 and at one end the shaft 20 carries a sprocket wheel 21, around which a short chain section 22 passes, the 65 chain section 22 being connected by rods or

cables 23 to the operating lever 5 at equal distances from the fulcrum thereof. At the other end the shaft 20 is provided with a crank 23^a which is connected by a pitman 24 with the extension 9 in the gate sections 3, while 70 the sprocket 21 also has a crank portion 23^b which connects with the extension arm 9 of the gate section 4 through the medium of a pitman 24^a, as shown.

Instead of constructing my improved gate 75 in the manner just described, which is the preferable construction for a wooden gate, I may make the same of metal, as shown in Fig. 2, of the drawings, by reference to which it will be seen that the various bars of the 80 gates are formed of pipe sections, otherwise the construction of this form of my invention is substantially the same as the other form with the exception that the extensions 9 are each made of one pipe section on which the 85 weights 10 may be adjusted along the same by a set screw 10^a, as shown. In both forms of my invention, as shown in Figs. 1, 2, 6 and 7, I may use wires 25, either barbed or plain, but for convenience of illustration, I have 90 simply indicated such wires as plain wires and indicated them on Figs. 2 and 7 of the drawings. The gate shown in Figs. 2 and 7 may be made either of plain pipe or made ornamented, as such ornamentation forms 95 no part of my present invention.

So far as described, the manner in which my invention operates, will be best explained as follows:—Assume the parts to be in the position shown in Fig. 1 and it is desired that 100 the gates be opened to permit passage therethrough; the operator grasps the hand engaging portion of the pull rod or cable which rocks the bell crank levers carried by the lever 5 and causes the motion thereof to be imparted to the latch raising member 13, which raises the latch 11 out of engagement with its locking bar 12^a, and as the operator continues pulling, the tilting of the bar 5 will turn the shaft 20 and cause the cranks to impart 105 such motion through the pitmen connections to the gate sections 3 and 4, rocking them on their pivots and raising the gates to the position shown in Figs. 6 to 7. As the gates reach their open position the notch 11^b of the latch 11 will engage the member 12^a and lock the gates in their open position, it being understood that when the gate section 4 is locked by the latch 11, no motion can be imparted to the gate 3 since it is held rigid through the 120 medium of the shaft connection 20 and the pitmen which connect the shaft 20 with the gate sections. After passing through the gate, however, the operator grasps the pull cord or rope at the other end of the lever 5 125 and pulls down on the member 6, causing the latch member 13 to release the latch 11 and permit the gates to be swung to their closed position as the bar 5 is again brought to its normal or horizontal position. It should be 130

stated that the latch releasing member 13 is preferably provided with a notch 13^x for the latch 11, as shown.

In Fig. 5, I have shown an enlarged detail 5 of a portion of the gate shown in Figs. 2 and 7, and showing the manner of connecting the pipes 3^a to the vertical pipes forming the abutting ends of the gate.

From the foregoing description, taken in 10 connection with the accompanying drawings, it is thought the complete construction, operation and numerous advantages of my invention will be readily understood by those skilled in the art to which the invention app- 15 pertains.

What I claim is,—

1. A gate comprising a pair of gate sections, means for mounting said sections to be swung in a vertical plane to open the gate, 20 means carried by one of said gate sections for locking said sections in its open or closed position, means carried by one of said gate sections and coöperatively engaging the other gate section for locking the gate sections together when closed, combined with means 25 for first releasing said first mentioned locking means and then upon further movement swinging the gate sections to their open position, substantially as shown and described.

2. The combination with a pair of vertically tilttable gate sections, and means co-operatively connecting said sections together to move in unison, of counterbalances for 30 each section, a pivoted latch member carried by one of said gate sections and adapted to engage a fixed latch bar to lock the gate sections in its open or closed position, and means for first releasing said gate sections to open or close the same, substantially as 35 shown and described.

3. The combination with the gate posts, of gate sections vertically tiltably mounted on said posts, a rotatable shaft and crank and pitmen connections between the rotatable 45 shaft and the gate sections, a rocking lever fulcrumed on one of said posts, connections between said rocking lever and said rotatable shaft, means carried by one of said gate sections for locking the same in its closed position, and means carried by the tilttable lever and coöperatively connected with the locking 50 means for releasing said locking means, substantially as shown and described.

4. The combination with the gate posts, of 55 gate sections vertically tiltably mounted on said posts, a rotatable shaft and crank and pitmen connections between the rotatable shaft and the gate sections, a rocking lever fulcrumed on one of said posts, connections 60 between said rocking lever and said rotatable shaft, means carried by one of said gate sections for locking the same in its closed position, and means carried by the tilttable lever and coöperatively connected with the locking 65 means for releasing said locking means be-

fore the tilting lever begins its tilting movement, substantially as shown and described.

5. The combination with the gate posts, of 70 gate sections vertically tiltably mounted on said posts, a rotatable shaft and crank and pitmen connections between the rotatable shaft and the gate sections, a rocking lever fulcrumed on one of said posts, connections 75 between said rocking lever and said rotatable shaft, means carried by one of said gate sections for locking the same in its closed position, and means carried by the tilttable lever and coöperatively connected with the locking means for releasing said locking means, and means carried by one of said gate sections for engaging the other gate section 80 when closed to lock the same in its closed position, substantially as shown and described.

6. An apparatus of the class described, comprising a pair of gate posts, vertically 85 tilttable gate sections pivotally mounted in said gate posts, said gate sections having abutting end bars, a center block adapted to be engaged by said end bars when the gate sections are closed, counter-balancing means 90 for said gate sections, a shaft receiving tube mounted beneath said gate sections, a rotatable shaft mounted in said tube, a crank on one end of said shaft, a pitman connection between said crank and one of said gate sections, a cranked sprocket wheel on the other 95 end of said shaft, pitmen connections between said cranked sprocket wheel and said other gate section, and means coöperating with said sprocket wheel for rotating said shaft to open 100 and close the gate sections.

7. An apparatus of the class described, comprising a pair of gate posts, vertically 105 tilttable gate sections pivotally mounted in said gate posts, said gate sections having abutting end bars, a center block adapted to be engaged by said end bars when the gate sections are closed, counter-balancing means 110 for said gate sections, a shaft receiving tube mounted beneath said gate section, a rotatable shaft mounted in said tube, a crank on one end of said shaft, a pitman connection between said crank and one of said gate sections, a cranked sprocket wheel on the other 115 end of said shaft, pitmen connections between said cranked sprocket wheel and said other gate section means coöperating with said sprocket wheel for rotating said shaft to open and close the gate sections, said last named means comprising a rockably mounted lever, chain and rod connections between said lever and said sprocket, substantially as shown and described.

8. An apparatus of the class described, comprising a pair of gate posts, vertically 125 tilttable gate sections pivotally mounted in said gate posts, said gate sections having abutting end bars, a center block adapted to be engaged by said end bars when the gate sections are closed, counter-balancing means 130

- for said gate sections, a shaft receiving tube mounted beneath said gate sections, a rotatable shaft mounted in said tube, a crank on one end of said shaft, pitman connections 5 between said crank and one of said gate sections, a cranked sprocket wheel on the other end of said shaft, pitmen connections between said cranked sprocket wheel and said other gate section, means for coöperating 10 with said sprocket wheel for rotating said shaft to open and close the gate, said last named means comprising a rockably mounted lever, chain and rod connections between the lever and said sprocket, means 15 for normally holding said gate sections locked, and means for first unlocking said gate sections and for upon further movement rocking said lever, substantially as shown and described.
- 20 9. An apparatus of the class described, comprising a pair of gate posts, vertically tiltable gate sections pivotally mounted in said gate posts, said gate sections having abutting end bars, a center block adapted 25 to be engaged by said end bars when the gate sections are closed, counter-balancing means for said gate sections, a shaft receiving tube mounted beneath said gate section, a rotatable shaft mounted in said tube, a crank 30 on one end of said shaft, pitman connec-

tions between said crank and one of said gate sections, a cranked sprocket wheel on the other end of said shaft, pitmen connections between said cranked sprocket wheel and said other gate sections, means 35 coöperating with said sprocket wheel for rotating said shaft to open and close the gate section, said last named means comprising a rockably mounted lever, chain and rod connections between said lever and said 40 sprocket, means for normally holding said gate sections locked, means for first unlocking said gate sections and then upon further movement rocking said lever, said locking means comprising a fixed latch bar, a pivoted 45 latch carried by one of said gate sections for engaging said fixed latch bar, and said lock-releasing means comprising a latch engaging member, a double bell crank lever carried centrally by said rocking lever and coöperatively connected with said latch engaging member, and means mounted at the ends of 50 said rocking member and coöperating with said double bell crank lever for operating the same, substantially as shown and described. 55
